CLAIM

The ornamental design for a remote activation device for security system, as shown and described.

DESCRIPTION

FIG. 1 is a front, top perspective view of a remote activation device for security system;

FIG. 2 is a back top perspective view thereof;

FIG. 3 is a front elevation view thereof;

FIG. 4 is a back elevation view thereof;

FIG. 5 is a right-side elevation view thereof;

FIG. 6 is a left-side elevation view thereof;

FIG. 7 is a top plan view thereof;

FIG. 8 is a bottom plan view thereof;

FIG. 9 is a front, top perspective view of a second embodiment of a remote activation device for security system;

FIG. 10 is a back, top perspective view thereof;

FIG. 11 is a front elevation view thereof;

FIG. 12 is a back elevation view thereof;

FIG. 13 is a right-side elevation view thereof;

FIG. 14 is a left-side elevation view thereof;

FIG. 15 is a top plan view thereof; and,

FIG. 16 is a bottom plan view thereof.

The dashed lines depict portions of the remote activation device for security system that form no part of the claimed design. The dot-dashed lines represent boundaries of the claimed remote activation device for security system and form no part of the claimed design.
